Primary Examiner — Sandra Snapp(74) Attorney, Agent, or Firm — Quarles & Brady LLP(57) CLAIM

The ornamental design for a seat portion, as shown and described.

DESCRIPTION

FIG. 1 is a left, top, front perspective view of a seat portion according to our new design, the bottom thereof is unseen in use;

FIG. 2 is a top, rear perspective view from the left side thereof;

FIG. 3 is a front elevational view thereof;

FIG. 4 is a rear elevational view thereof;

FIG. 5 is a left side elevational view thereof; and,

FIG. 6 is a top plan view thereof.

The broken line representations in the figures are for the purpose of illustrating unclaimed boundaries. The broken lines are thus not part of the claim.

The nature of this product is a portion of seating furniture, for example a chair, lounge, couch and the like.
